UNITED STATES PATENT OFFICE.

WILLIAM HOLMES, OF NIAGARA FALLS, ONTARIO, CANADA.

COMBINED AUTO JACK AND WHEEL PULLER.

1,412,180.

Specification of Letters Patent. Patented Apr. 11, 1922.

Application filed September 16, 1920. Serial No. 410,756.

To all whom it may concern:

Be it known that I, WILLIAM HOLMES, of the city of Niagara Falls, in the county of Welland, Province of Ontario, Canada, a subject of the King of Great Britain, have invented certain new and useful Improvements in Combined Auto Jacks and Wheel Pullers, of which the following is a specification.

10 My invention relates to improvements in combined auto jacks and wheel pullers, and relates more particularly to that type of jack in which a jack-screw is used, and the object of the invention is to provide a 15 double-utility tool which can be used for jacking purposes, and which can also be used to remove a wheel from the axle carrying the same.

In putting my invention into practice, I 20 make certain modifications in the construction of the barrel of a well-known form of jack, and mount on the jack-screw a nut which is prevented from rotation on the said screw from the fact that it conforms to 25 the internal shape of the barrel. This nut when the tool is used for jacking purposes is locked to the jack-screw at the lower end thereof so that the jack-screw may be raised and lowered in the usual way without rotation. When the tool is used as a wheel 30 puller, the base thereof is adapted to co-act with the hub of the wheel and the said nut is uncoupled from the jack-screw to permit the turning of the screw in order to ultimately locate the said nut against the 35 internal stop located at the upper end of the barrel. The continued rotation of the jack-screw in the proper direction will bring the same in contact with the axle and so exert 40 force as to remove the wheel therefrom.

In the following specification I shall describe my preferred form of construction whereby I provide a double-utility tool of the class set forth, and what I claim as new 45 will be set forth in the claims forming part of this specification.

Figure 1 is in part a vertical central longitudinal section through the barrel of the tool adapted for use as a wheel puller in 50 combination with the jack-screw which is shown in side elevation. Figure 2 is a side elevation of the tool adapted for use as a jack showing portion of the base in section, and Figure 3 is a horizontal cross-section 55 on the line 3—3, Figure 1.

In the drawings like characters of reference refer to the same parts.

A is the barrel of the tool, and mounted to have vertical movement therein is the jack-screw B. This jack-screw does not have threaded engagement with the barrel A. C is the base of the barrel. D is a bevelled wheel the hub E of which has threaded engagement with the jack-screw B, and rests normally against the upper end a of the barrel A. F is a bevelled wheel mounted on the stud G. The wheel F is in mesh with the wheel D, and when rotated rotates the wheel D to raise or lower the jack-screw B for the purpose of moving a vehicle or other suitable body.

Any suitable means may be used to rotate the wheel F, for instance, a toothed wheel H also mounted on the stud G, which wheel can be rotated in either direction by the pawl I pivoted at J to the lug 2 carried by the handle or lever 3; the construction just described is well known.

To prevent the rotation of the jack-screw B, I form the internal bore 4 of the barrel A preferably hexagonal in cross-section, and mount on the jack-screw B a nut 5 adapted to fit the said bore. By any suitable means such as a set-screw 6, the nut 5 is locked to the jack-screw B. The construction just described prevents the rotation of the jack-screw B as just mentioned but yet permits of the free vertical movement thereof.

Now in order to adapt the tool to be used as a wheel puller, I split the base C at one side as shown at 7 and provide two exterior lugs 8 through which the screw 9 operates. I internally thread the base C as shown at 10 so as to permit the base to be screwed onto the hub 11 of the wheel 12. When said base is positioned the same is tightly clamped around said hub through the medium of the lugs 8 and screw 9. Previously to this, the nut 5 has been unlocked from the jack-screw B, and the said screw turned until the 100 said nut is located against a stop 13 in the form of an annular shoulder formed near the upper end of the barrel A and interiorly thereof. The set-screw 6 or equivalent fastening means, in this use of the tool, is not 105 required to function. Through continued rotation of the jack-screw B the thrust between the nut 5 and stop 13 will cause the said jack-screw to approach the axle 14 and in due course come in contact therewith, and 110

the result will be that the wheel 12 will be removed from said axle.

Any suitable construction may be employed to permit the jack-screw B to be rotated when the tool is used as a wheel puller: a cheap yet efficient construction for this purpose consists in providing the jack-screw with a nut 15 integrally formed therewith around which a wrench or spanner can be placed.

It will be clear to one skilled in the art that the tool can be readily removed from the hub 11, and the nut 5 moved to the bottom of the jack-screw B so as to adapt the tool to perform the function of a jack.

The bore b of the upper end of the barrel A of course communicates with the bore 4, and is plane and substantially circular in cross-section.

20 What I claim as my invention is:

1. A combined jack and wheel puller comprising a bore-provided barrel interiorly non circular in cross-section for the greater portion of its length and terminating at its upper end in a plane bore of smaller diameter thus forming an internal annular stop; an internally threaded base carried by said barrel and adapted to be clamped around the hub of a wheel; a jack-screw mounted to have longitudinal movement within said barrel; a nut adapted to fit the bore of said barrel below said stop, and threaded on said screw and adapted to be brought into contact with said stop through the rotation of said screw and to co-act therewith to permit said screw to ultimately be brought into contact with the axle from which a wheel is to be removed.

below said stop, and adapted to be keyed to said jack-screw and located near the lower end thereof when the tool is used for lifting purposes, said nut being uncoupled from said jack-screw and moved through the rotation thereof into contact with said stop so that as said jack-screw is rotated it will be brought into contact with the axle of the wheel to be removed, and means adapted to coact with said jack-screw to permit the same to be moved to effect the different functions of the tool according to the use thereof.

2. A wheel puller comprising a bore-provided barrel interiorly non circular in cross-section for the greater portion of its length and terminating at its upper end in a plane bore of smaller diameter thus forming an internal annular stop; an internally threaded base carried by said barrel and adapted to be clamped around the hub of a wheel; a jack-screw mounted to have longitudinal movement within said barrel; a nut adapted to fit the bore of said barrel below said stop, and threaded on said screw and adapted to be brought into contact with said stop through the rotation of said screw and to co-act therewith to permit said screw to ultimately be brought into contact with the axle from which a wheel is to be removed.

WILLIAM HOLMES.
